CLAIM

The ornamental design for a wire reel shaft, as shown and described.

DESCRIPTION

FIG. 1 is a side perspective view of a wire reel shaft showing our new design;

FIG. 2 is a front view thereof, the rear view being a mirror image, therefore not shown;

FIG. 3 is a top view thereof, the bottom view being a mirror image, therefore not shown;

FIG. 4 is a left side view thereof, the right side being a mirror image, therefore not shown; and,

FIG. 5 is another side perspective view thereof shown in an environment of use.

The broken lines shown in FIG. 5 are for purposes of illustrating environmental subject matter only, and form no part of the claimed design.

The shade lines in the figures show contour and not surface ornamentation.

1 Claim, 3 Drawing Sheets
